UNITED STATES PATENT OFFICE.

JOHN GARDNER, OF NEW HAVEN, CONNECTICUT, ASSIGNOR TO THE
WINCHESTER REPEATING ARMS COMPANY, OF SAME PLACE.

PRIMER FOR CARTRIDGES.

SPECIFICATION forming part of Letters Patent No. 653,953, dated July 17, 1900.

Application filed January 2, 1900. Serial No. 19. (No model.)

To all whom it may concern:

Be it known that I, JOHN GARDNER, of New Haven, in the county of New Haven and State of Connecticut, have invented a new Improvement in Primers for Cartridges; and I do hereby declare the following, when taken in connection with the accompanying drawings and the letters of reference marked thereon, to be a full, clear, and exact description of the same, 10 and which said drawings constitute part of this specification, and represent, in—

Figure 1, a sectional view of a primer constructed in accordance with my invention; Fig. 2, a corresponding view of a modification thereof.

My invention relates to an improvement in primers for cartridges, the object being to produce primers of more exact uniformity than those now made and of superior safety.

With these ends in view my invention consists in a primer having a sheet-metal cap and an anvil, one of which parts is formed with a locating-shoulder coacting with the other part to secure for the anvil an invariable location with reference to the fulminate in the cap and to prevent the anvil from movement toward the fulminate under any jarring of the primer.

My invention further consists in certain details of construction and combinations of parts, as will be hereinafter described, and pointed out in the claim.

In carrying out my invention as shown in Fig. 1 I form the rigid sheet-metal flat anvil A upon its opposite edges with locating-shoulders $a a$, produced by reducing the anvil in width and arranged to be seated upon an annular locating-shoulder b , formed within the sheet-metal cap B, which may be otherwise of any approved construction, but which, as herein shown, has an upset head B' and a contracted outer end B'' , which, in being contracted or reduced in diameter, engages with the arms $A' A'$ at the outer end of the anvil and forces the locating-shoulders $a a$ thereof home to a firm bearing upon the annular locating-shoulder b of the cap. By making the anvil correspond in width to the internal diameter of the cap the edges of the anvil are brought to bear upon the inner faces of the side walls of the cap, whereby the anvil is securely held

against any rocking movement. The anvil being flat and occupying only a portion of the space inclosed by the cap, there is ample opportunity for the fire produced by the burning of the fulminate to pass out of the cap on opposite sides of the anvil, which, so far as the operation of the primer is concerned, need not leave the cap at all. It will be readily understood that under this construction the anvils will always occupy an exact predetermined position within the caps, whereby great uniformity in the product is secured. This construction also has a further advantage in that under no circumstances can the anvil move longitudinally, and is therefore maintained in a fixed position with reference to the fulminate C, into which the point a' of the anvil very slightly projects.

In the construction shown by Fig. 2 of the drawings the anvil A and cap B are shorter than as shown in Fig. 1, and the outer end of the cap is not closed over the outer end of the anvil, so as to hold the same against longitudinal movement in that direction; but the anvil is formed, as before, with locating-shoulders $a a$, designed to be seated upon an annular locating-shoulder b , formed within the cap B. In this construction also the anvils will always be located in a predetermined position within the caps, so far as the fulminate C is concerned, which is the main point. The movement of the anvil in the other direction may be restrained either by friction between the edges of the anvil and the cap or in some other way.

In view of the modifications suggested I would have it understood that I do not limit myself to the exact construction herein shown and described, but hold myself at liberty to make such alterations as fairly fall within the spirit and scope of my invention.

I am aware that it is old to locate a sheet-metal anvil within the outer end of the shell of a shotgun-cartridge, the said anvil being provided with projections entering the shell to prevent the anvil from longitudinal movement therein. This anvil is formed with an outwardly-projecting part constituting the anvil proper and entering the primer, which is located in a pocket formed for its reception in an independently-formed head which is

applied to the outer end of the shell, so as to inclose that portion of the shell containing the anvil. The construction thus described provides for giving a firm seat to the 5 anvil, but does not and can not secure that accuracy of relation between the anvil and the fulminate which it is the prime object of my invention to achieve. I do not therefore 10 claim as constituting any part of my invention the rigid holding of an anvil within the shell proper of a cartridge, but limit my claim to the holding of an anvil within the primer-cap itself in such a way as to secure an invariable location between the anvil and the fulminate and to prevent the anvil from movement toward the fulminate under any jarring 15 of the primer.

Having fully described my invention, what I claim as new, and desire to secure by Letters 20 Patent, is—

A primer having its sheet-metal cap formed with an annular locating-shoulder, and provided with a rigid, flat, sheet-metal anvil the

edges of which bear upon the inner faces of the cap, and which is reduced in width for 25 the formation upon its opposite edges of locating-shoulders adapted to be seated upon the said shoulder of the cap, whereby the anvil is not only supported against sidewise deflection throughout its length, but is brought 30 to a predetermined position with respect to the cap and with respect to the fulminate contained in the head thereof, the said primer being adapted to be inserted bodily into a pocket formed for its reception in the head 35 of a cartridge-shell, and the fire produced by the ignition of the fulminate passing out of the cap on opposite sides of the anvil.

In testimony whereof I have signed this specification in the presence of two subscribing 40 witnesses.

JOHN GARDNER.
